UNITED STATES PATENT OFFICE.

FREDERICK W. SCHEIFELE, OF AUDUBON, NEW JERSEY.

CRUDE-OIL BURNER.

Application filed May 23, 1925. Serial No. 32,333.

To all whom it may concern:

Be it known that I, FREDERICK W. SCHEIFELE, a citizen of the United States, residing at Audubon, in the county of Camden and State of New Jersey, have invented certain new and useful Improvements in Crude-Oil Burners, of which the following is a specification, reference being had to the accompanying drawings.

10 This invention relates to crude oil burners and has for an important object thereof an improvement upon the burner structure, shown in my co-pending application, Serial No. 748,226, filed November 6, 1924, for 15 crude oil burners.

Specifically, it is the object of the present invention to provide in a device having a blower supplying a draft of air to the burner, and connections between the burner 20 and the blower conducting the air from the blower to the burner whereby a portion of the smoke and flame are aspirated and drawn through the connection to the burner together with the air from the blower, a 25 construction such that the aspirator is included directly in the construction of the burner proper.

A further object of the invention is to provide in combination with a device of this 30 character which is arranged within a fire box means whereby a portion of the contents of the fire box is likewise drawn into the air from the blower and supplied to the burner.

35 A still further object of the invention is to provide in a device of this character a novel and improved means for heating the oil pipe leading to the burner.

These and other objects I attain by the 40 construction shown in the accompanying drawings, wherein for the purpose of illustration is shown a preferred embodiment of my invention and wherein:

Figure 1 is a plan view of an oil burning apparatus constructed in accordance 45 with my invention;

Figure 2 is a side elevation thereof, indicating the position of the burner within the fire box;

50 Figure 3 is a vertical sectional view through the burner proper taken on the line 3-3 of Figure 1;

Figure 4 is a section on the line 4-4 of Figure 1; and

55 Figure 5 is a reduced section on the line 5-5 of Figure 3.

Referring now more particularly to the drawings, the oil burning apparatus includes a burner section 10 adapted to be arranged within a fire box, the walls of 60 which are generally designated at 11 and 12 a control unit having a pump 13 for providing a forced draft of air to the burner and an oil supply line and controls therefor, generally designated at 14 and a gas 65 line 15. The construction of the control unit is fully set forth in my former application and does not enter into the present invention except in combination with the particular burner construction 10 which is employed.

The burner unit comprises a body casting 16 and a cap 17. The body casting 16 is formed to provide a vertically extending cylindrical burner chamber 18 having an open 75 top and adjacent the bottom of its side wall an inlet opening 19. Upon the exterior of this chamber, vertically extending conduits 20 and 21 are formed, these conduits being 80 diametrically opposed and the conduit 20 85 aligning with and communicating at its lower end with the inlet 19. The conduit 21 has a horizontal extension 22 underlying the burner chamber 18 and extending diametrically thereof, the outer end of this conduit 90 projecting slightly beyond the wall of the chamber and being provided with an axial inlet 23 and an upwardly facing inlet 24 arranged in the same sectional plane as the conduits 20, 21 and the inlet 19. The inlet 95 23 of the extension 22 of the conduit 21 is connected with a conduit 25 to the blower pump 13.

The actual burner, generally designated at 26, has a wall 27 abutting the wall of the 100 burner chamber 18 above the inlet 19 and is of less width than such inlet. At its bottom, this wall is provided with a horizontally disposed shelf 28 extending into the chamber 18 and increasing in width as it extends 105 into the chamber. The lower surface of this shelf preferably rests directly upon the bottom of the chamber. The rear edge of this shelf or that edge remote from the wall 27 has formed thereon an upstanding rib or 110 flange 29, the purpose of which will presently appear. Above the shelf 28 is formed what may be termed a generator shelf 30 which is of less length from front to back than the shelf 28 and is connected with the shelf along its side edges by side walls 31, these side walls combining with

the flange 29 and vertical front wall 27 to provide upon the upper surface of the shelf 28 a pocket for the collection of oil. The rear edge of the shelf 30 is notched, as at 32. 5 The vertical wall 27 has formed therein above the shelf 30 an opening 33. Between the shelves 28 and 30 is a second horizontal opening 34. These openings, when the burner 26 is in proper position in the chamber 18, have their axes directed through the inlet 19 of the burner chamber.

In the outer wall of the conduit 20 is formed an opening 35 of greater size than the opening 33 and axially aligning with 15 this opening. A second opening 36 is also formed in this wall of the same size as the opening 34 of the burner and a third opening 37, the purpose of which will presently appear. With the opening 35 is engaged 20 a conduit 38 through which is directed an oil pipe 39, the inner end of which projects through the opening 33 of the burner to discharge upon the upper shelf 30. The outer end of the conduit 38 is sealed to the oil pipe 39, as at 40, and simply forms a chamber through which heat from the burner may circulate to warm the oil within the oil pipe. Through the openings 36 and 34, the gas pipe 15 is directed to provide a pilot flame 25 for the burner. In the opening 37, a conduit 41 is engaged for carrying overflow oil from the burner to an automatic cut-off device, generally designated at 42. Attention is directed to the fact that the several conduits 38, 39, 15 and 41 all extend above the 30 inlet 24 of the branch 22 of the conduit 21 which is in communication with the interior of the fire box.

The burner cap includes a cover 43 for the 40 burner chamber 18 having a central opening 44 of less size than the mouth of the opening of the burner chamber. Secured to this cover at diametrically opposed points are vertically extending legs 45 and 46 of a U-shaped conduit, the bight portion 47 of which is subdivided to form two channels 48 and 49. The channel 48 connects the upper ends of the legs 45 and 46 while the channel 49 communicates at one end with 45 the leg 45 and at its opposite end with a downwardly facing opening 50 formed in the under surface of the bight portion 47 and of less size than the cap opening 44 which it opposes in spaced relation. At the 50 under surface of the bight portion and at the sides thereof, horizontally projecting wing flanges 51 are formed, providing a spreader plate so that products of combustion passing from the opening 44 and not entering the opening 50 will be spread within the fire box in which the burner is located.

In the operation of the burner, the blower forcing a draft through the conduit 25, leg 22, extension 22 of conduit 21, conduit 21, leg 46, channel 48, leg 45 and conduit 20 to

the burner chamber 18 produces an aspirating effect at the inlet 24 of the extension 22, drawing a portion of the contents of the fire box into the air from the blower. It also produces an aspirating effect at the point of 70 communication between the channel 49 and the leg 45, causing suction at the opening 50 which will draw a portion of the products of combustion from the burner chamber 18 into the channel 49 to mingle with the air 75 passing to the inlet of the burner. Since the contents of the fire box will be heated, the current of heated air passing about the pipes 38, 15 and 41 will cause these pipes to be heated and will, in addition, heat incoming air. This incoming air is still further heated when the products of combustion are added thereto by the products of combustion from the channel 49, so that the mixture delivered to the burner is highly heated 80 and will serve to volatilize the oil and readily intermingle therewith. The burner 26 which is described in my previous application, by reason of its construction, will cause the incoming air to circulate within 85 the burner chamber so that it more readily intermingles with the volatilized oil to make for perfect combustion. It will be obvious that the cap will become highly heated and serve to further heat the incoming air after 90 the burner has been in operation for a short while. Attention is directed to the fact that by the construction hereinbefore described, both the aspirator and goose-neck of my former application are produced directly in 95 the burner, the goose-neck being represented by the opening 50 and passage 49 and the aspirator by the outlet of the passage 49 at the junction of the passage 48 with the leg 45.

Since the structure hereinbefore set forth is obviously capable of a certain range of change and modification without materially departing from the spirit of my invention, I do not limit myself to such specific structure except as hereinafter claimed.

I claim:

1. In a crude oil burner, a casting formed to provide a vertically extending open topped burner chamber having an inlet adjacent the lower end thereof, a conduit for supplying a forced draft of air to the inlet of the burner chamber, a cap for the chamber including a portion of said conduit and having a vertical opening of less size than the opening of the burner chamber, a goose-neck conduit carried by the cap having one end thereof opposed to the opening of the burner cap and its opposite end connected to said portion of the first named conduit whereby products of combustion will be aspirated therethrough.

2. In a crude oil burner, a casting formed to provide a vertically extending open topped burner chamber having an inlet ad-

1 jacent the lower end thereof, a conduit for
2 supplying a forced draft of air to the inlet
3 of the burner chamber, a cap for the chamber
4 having a vertical opening of less size
5 than the burner chamber, said cap includ-
6 ing a U-shaped conduit, the bight portion
7 of which overlies such vertical opening, said
8 conduit forming a portion of the first
9 named conduit and a goose-neck conduit
10 likewise carried by the cap and having one
11 end thereof directly opposed to the opening
12 of the cap and the opposite end thereof in
13 aspirating communication with said portion
14 of the first named conduit.

15 3. In a crude oil burner, a casting formed
16 to provide a vertically extending open
17 topped burner chamber having an inlet ad-
18 jacent the lower end thereof, a conduit for
19 supplying a forced draft of air to the inlet
20 of the burner chamber, a cap for the burner
21 chamber including a U-shaped conduit
22 section forming a portion of the first named
23 conduit, said cap having a vertical opening
24 of less size than the chamber, the bight por-
25 tion of said U-shaped conduit section being
26 opposed to the opening of the cap and be-
27 ing subdivided to provide two channels, one
28 of said channels communicating at one end
29 with an opening formed in the bight por-
30 tion of the U-shaped conduit section in op-
31 position to the opening of the cap and at
32 its opposite end with the outlet leg of the
33 U-shaped conduit, the other of said chan-
34 nels connecting the inlet and outlet legs of
35 said U-shaped conduit.

36 4. In a crude oil burner, a casting formed
37 to provide a vertically extending open
38 topped burner chamber having upon its outer
39 wall a pair of spaced vertically extending
40 conduits, an inlet for the burner chamber
41 adjacent the lower end thereof with which
42 one of said conduits communicates, means
43 for connecting the other of the conduits
44 with a source of forced draft, a cap for
45 the burner chamber having an opening of
46 less size than the opening of the burner
47 chamber and including a U-shaped conduit
48 section the legs of which communicate with
49 the conduits of the burner chamber and the
50 bight portion of which is opposed to the
51 opening of the cap, said bight portion being
52 subdivided into two channels one of which
53 connects said legs and the other of which
54 communicates with the outlet leg of the U-
55 shaped conduit at one end and at its oppo-
56 site end has an opening in opposition to
57 the opening of the cap.

58 5. In a crude oil burner, a casting formed
59 to provide a vertically extending open
60 topped burner chamber having in its outer
61 wall a pair of spaced vertically extending
62 conduits one of which is provided with a
63 branch extending transversely of the bot-
64 tom of the burner chamber and extended
65 beyond the burner chamber wall, said branch
66 at its extension having a vertically directed
67 opening and a horizontally directed open-
68 ing, the last named opening being adapted
69 for connection with a blower, said burner
70 chamber having an inlet formed therein ad-
71 jacent the bottom thereof with which the
72 other of said conduits communicates, a
73 burner within the chamber, feed pipes for
74 the burner extending through the wall of
75 the last named conduit and said inlet and
76 a cap for the burner including a U-shaped
77 conduit having its bight extended above the
78 top of the burner and its legs in communi-
79 cation with the conduits of the burner
80 chamber.

81 6. In a crude oil burner, a casting formed
82 to provide a vertically extending open
83 topped burner chamber having in its outer
84 wall a pair of spaced vertically extending
85 conduits one of which is provided with a
86 branch extending transversely of the bot-
87 tom of the burner chamber and extended
88 beyond the burner chamber wall, said branch
89 at its extension having a vertically directed
90 opening and a horizontally directed open-
91 ing, the last named opening being adapted
92 for connection with a blower, said burner
93 chamber having an inlet formed therein ad-
94 jacent the bottom thereof with which the
95 other of said conduits communicates, a
96 burner within the chamber, feed pipes for
97 the burner extending through the wall of
98 the last named conduit and said inlet and
99 a cap for the burner including a U-shaped
100 conduit having its bight extended above the
101 top of the burner and its legs in communi-
102 cation with the conduits of the burner
103 chamber, said bight portion being
104 subdivided into two channels one of which
105 connects said legs and the other of which
106 communicates with the outlet leg of the U-
107 shaped conduit at one end and at its oppo-
108 site end has an opening in opposition to the
109 mouth of the burner chamber.

110 7. In a crude oil burner, a casting formed
111 to provide a vertically extending open
112 topped burner chamber having an inlet ad-
113 jacent the lower end thereof, a conduit for
114 supplying a forced draft of air to the inlet
115 of the burner chamber, a cap for the chamber
116 having a vertical opening of less size
117 than the burner chamber, said cap includ-
118 ing a U-shaped conduit, the bight portion
119 of which overlies such vertical opening, said
120 conduit forming a portion of the first named
121 conduit, a goose-neck conduit likewise car-
122 ried by the cap and having one end there-
123 of directly opposed to the opening of the
124 cap and the opposite end thereof in aspirat-
125 ing communication with said portion of the
126 first named conduit, and wing flanges ex-
127 tends at opposite sides of the bight por-
128 tion of the U-shaped conduit and providing
129 a flame spreader.

130 8. In a crude oil burner, a casting formed

to provide a vertically extending open topped burner chamber having upon its outer wall a pair of spaced vertically extending conduits, an inlet for the burner chamber adjacent the lower end thereof with which one of said conduits communicates, means for connecting the other of the conduits with a source of forced draft, a cap for the burner chamber having an opening of less size than the diameter and including a U-shaped conduit section the legs of which communicate with the conduits of the burner chamber and the bight portion of which

is opposed to the opening of the cap, said bight portion being subdivided into two channels one of which connects said legs and the other of which communicates with the outlet leg of the U-shaped conduit at one end and at its opposite end has an opening in opposition to the opening of the cap, and wing flanges extending at opposite sides of the bight portion of the U-shaped conduit and providing a flame spreader. 15 20

In testimony whereof I hereunto affix my signature.

FREDERICK W. SCHEIFELE.
